UNITED STATES PATENT OFFICE

171,598

DISPENSER FOR SMALL ARTICLES

Francis Edward Herrmann, Altadena, Calif., assignor to Max Factor & Co., Hollywood, Calif., a corporation of Delaware

Application July 6, 1953, Serial No. 25,810

Term of patent 14 years

(Cl. D52—2)

To all whom it may concern:

Be it known that I, Francis Edward Herrmann, a citizen of the United States of America, residing at Altadena, in the county of Los Angeles and State of California, have invented a new, original, and ornamental Design for a Dispenser for Small Articles, of which the following is a specification, reference being had to the accompanying drawing, forming a part thereof.

Figure 1 is a perspective view of a dispenser for small articles, showing my new design.

Figure 2 is a rear elevation.

Figure 3 is a side elevation.

I claim:

The ornamental design for a dispenser for small articles, as shown.

FRANCIS EDWARD HERRMANN.
